UNITED STATES PATENT OFFICE.

VINCENT P. KILL, OF LAWTON, OKLAHOMA, ASSIGNOR OF ONE-HALF TO CLARA R. OELBERG, OF KIRBY, OHIO.

WATER-CIRCULATING SYSTEM FOR THE COOLING JACKETS OF INTERNAL-COMBUSTION ENGINES.

Application filed September 11, 1926. Serial No. 134,846.

This invention relates to water circulating systems for the cooling jackets of internal combustion engines.

An important object of the invention is to provide a device of this character employing a portion of the explosive pressure generated in the cylinder of the engine and so constructed that the heat which would ordinarily be transmitted to the cooling fluid is dissipated and prevented from acting thereon.

A further object of the invention is to provide a device of this character in which the rate of circulation can be regulated and the possibility of the cooling fluid entering the cylinders is prevented.

A further object of the invention is to provide a device of this character including means relieving the cylinders of the engine to permit ready starting or permitting admission to the cylinder of a lubricant or priming fluid.

These and other objects I attain by the construction shown in the accompanying drawings, wherein for the purpose of illustration is shown a preferred embodiment of my invention and wherein:

Figure 1 is a side elevation of an internal combustion engine having my improvements applied thereto;

Figure 2 is a vertical section of the heat absorber;

Figure 3 is a sectional view through the check valve casing and check valve.

Referring now more particularly to the drawings, the numeral 10 indicates the water jacketed cylinder of an internal combustion engine and 11 the head thereof. With the water jacket of the cylinder communicates one end of an inlet pipe 12, the opposite end of which communicates with a supply tank 13 of any suitable construction. With the outlet of the water jacket one end of an outlet pipe 14 communicates, this outlet pipe being extended above the level of water within the tank 13 and communicating with the upper end of the tank, as indicated at 15.

In accordance with my invention, I connect with the interior of the cylinder of the engine through the head 11 a small conduit 16, which small conduit communicates through a heat absorber 17 and check valve 18 with one end of a conduit 19, the oppo-

site end of which communicates with the water jacket at the approximate center thereof, as indicated at 20. In the conduit 19 is arranged a control valve 21. The heat absorber element comprises a relatively heavy body having an inlet 22 and an outlet 23 at opposite ends thereof.

The body is formed interiorly with longitudinally extending passages 24 and 25 which are offset with respect to the inlet 22 and both of which communicate with the inlet 22. The passage 24 at its upper end is likewise connected with the outlet 23, while the passage 25 is blind and communicates through a supplemental outlet 26 with a manually operable relief valve 27. The exterior of the body may be provided with cooling vanes 28, such as are ordinarily applied to the cylinders of air cooled internal combustion engines, if so desired. At each explosion of the engine, a portion of the heated gases from the cylinder pass upwardly into the heat absorber and through the channel 24 and outlet 23 to the check valve. The check valve is lifted by the force of the explosion and this force may be thus exerted against the body of the fluid contained within the water jacket, causing circulation thereof. The heat of the gases is collected by the head of the body and dissipated to the atmosphere. The check valve 18 is preferably provided with a relatively heavy body, which likewise serves in dissipating the heat. This check valve further assists in preventing fluid from "backing up" through the heat absorber into the cylinders of the engine. In starting the engine, if it is desired to prime or lubricate the same, lubricant can be introduced through the relief valve 27 to the cylinder. The conduit 19 at some portion of its length must project above the highest point of the contact 14 in order to further reduce the possibility of any of the cooling fluids reaching the cylinders. In operation the gases entering the water jacket force the water through pipes 14 and 15 to the tank. Water thus displaced is replaced by water entering through the pipe 12.

It will be obvious that the construction hereinbefore set forth is capable of a certain range of change and modification without materially departing from the spirit of the invention and I do not wish to limit myself

to such specific structure except as herein-after claimed.

I claim:

1. In combination with a water jacketed internal combustion engine, a fluid supply tank for the water jacket, inlet and outlet pipes communicating with the water jacket and with said tank, the outlet pipe extending above the level of water within the tank, a conduit in communication with the interior of the cylinder of the engine and with the water jacket of the engine for directly transmitting a portion of the explosive force from the cylinder to the water jacket and means in said conduit for dissipating the heat of explosive gases from the engine passing therethrough comprising a relatively heavy metallic body having a passage for the gases, said passage being offset between the inlet and outlet of the body to thereby permit the heat of the gases to be absorbed by the body, the exterior of the body having cooling vanes.
2. In combination with a water jacketed in-

ternal combustion engine, a fluid supply tank for the water jacket, inlet and outlet pipes communicating with the water jacket and with said tank, the outlet pipe extending above the level of water within the tank, a conduit in communication with the interior of the cylinder of the engine and with the water jacket of the engine for directly transmitting a portion of the explosive force from the cylinder to the water jacket, means in said conduit for dissipating the heat of explosive gases from the engine passing therethrough comprising a relatively heavy metallic body having a passage for the gases, said passage being offset between the inlet and outlet of the body to thereby permit the heat of the gases to be absorbed by the body and a second passage communicating with the inlet of the body at one end, there being a manually operable relief valve in communication with said second passage.

In testimony whereof I hereunto affix my signature.

VINCENT P. KILL.
